No. 823,661.

PATENTED JUNE 19, 1906.

J. ANDERSON.
TRACE.
APPLICATION FILED AUG. 23, 1905.

UNITED STATES PATENT OFFICE.

JAMES ANDERSON, OF HARRODSBURG, KENTUCKY.

TRACE.

No. 823,661.

Specification of Letters Patent

Patented June 19, 1906.

Application filed August 23, 1905. Serial No. 275,497.

To all whom it may concern.

Be it known that I, JAMES ANDERSON, a citizen of the United States, residing at Harrodsburg, in the county of Mercer and State 5 of Kentucky, have invented new and useful Improvements in Traces, of which the following is a specification.

My invention pertains to traces, and more particularly to what are known as "trace-eye" protectors; and it has for one of its objects the provision of a sectional trace-eye protector calculated to lend itself to the flexibility of the trace and permit of the same being placed on swingletrees of different sizes 15 with facility.

Another object of the invention is the provision of a trace-eye protector which in addition to protecting the eye and prolonging the usefulness of the trace is adapted to enhance 20 the finished appearance of the trace and a harness as a whole.

With the foregoing in mind the invention will be fully understood from the following description and claims when taken in connection 25 with the accompanying drawings, forming part of this specification, in which—

Figure 1 is a perspective view of so much of a trace as is necessary to illustrate the preferred embodiment of my invention. Fig. 2 30 is a longitudinal central section of the trace. Fig. 3 is a transverse section of the same, and Fig. 4 is a detail view of one of the protectors removed.

Similar letters designate corresponding 35 parts in all of the views of the drawings, referring to which—

A is a trace which is preferably formed of connected layers of leather and is provided with two eyes a, designed to receive the end 40 of a swingletree or the like.

B B are trace-eye protectors constructed in accordance with my invention, and C is a link interposed between and connected to the protectors and designed to distribute strain 45 between the two.

The trace-eye protectors B are identical in construction, and therefore a detailed description of the protector shown in Figs. 3 and 4 will suffice to impart a definite understand- 50 ing of both. The said protector, Figs. 3 and 4, comprises angular sections b, having reduced and lapped ends c and pins d pivotally connecting the lapped ends of the sections and adapted to serve the additional purpose 55 of connecting the sections to the trace. The pins c are carried transversely through the

trace and have their ends secured at the opposite side of one layer of the trace with reference to the sections b by clenching, as indicated by e, or other means compatible with 60 the purpose of my invention. It will be readily apparent from the foregoing that the flexible connection of the sections b renders the protector as a whole flexible, with the result that the protector does not rob the trace 65 of the flexibility possessed by the leather. From this it follows that either of the eyes surrounded by the protectors may be readily placed on swingletrees of different sizes, which is an important desideratum. While this is 70 so, however, the protectors enable the eyes to retain the trace on the swingletrees.

It will be gathered from the foregoing that my improved trace-eye protectors not only prevent the eyes of the trace from becoming 75 unduly large or breaking out, but also increase the finish of the trace, and thereby add to the finished appearance of the harness of which the trace is a part. This latter is particularly true when the sections b of the protectors are japanned, nickel-plated, or otherwise embellished.

With a view of adding to the strength and durability of the trace when the same is provided with two of the protectors B, I provide 85 the before-mentioned link C. This link is pivotally connected to the adjacent ends of the protectors by two of the pins d, before described. By virtue of this it will be apparent that the link without detracting from the 90 flexibility of the trace is adapted to distribute strain between the two protectors when the eye surrounded by the rear protector is placed to receive the end of a swingletree.

While I have shown my novel protectors B 95 and link C as arranged at the outer side of a trace, I desire it distinctly understood that the said protectors may be countersunk in the trace or arranged in any other manner in or on the trace without involving a departure 100 from the scope of my invention.

Having described my invention, what I claim, and desire to secure by Letters Patent, is—

1. The combination with a trace having an eye; of a protector surrounding the said eye; the said protector comprising sections flexibly connected together and to the trace. 105
2. The combination with a trace having an eye; of a protector surrounding the eye and comprising sections having their meeting ends lapped, and transverse pivot-pins ex- 110

tending through the lapped ends of the sections, and also through the trace and secured to the latter.

3. The combination with a trace having 5 eyes; of protectors surrounding the eyes and respectively comprising sections flexibly connected together and to the trace, and a link interposed between and pivotally connected to the adjacent ends of the protectors.
- 10 4. The combination with a trace having eyes; of protectors surrounding the eyes and respectively comprising sections having their meeting ends lapped and transverse pivot-

15 pins extending through the lapped ends of the sections and also through the trace and secured to the latter, and a link interposed between the protectors and pivotally connected to the same by two of the said pins.

In testimony whereof I have hereunto set my hand in presence of two subscribing wit- 20 nesses.

JAMES ANDERSON.
